UNITED STATES PATENT OFFICE.

FRANK McCARTY, OF MARTIN'S FERRY, OHIO, ASSIGNOR OF ONE-HALF TO
CHARLES D. McCARTY, OF WHEELING, WEST VIRGINIA.

HEATER.

SPECIFICATION forming part of Letters Patent No. 552,483, dated December 31, 1895.

Application filed May 4, 1895. Serial No. 548,105. (No model.)

To all whom it may concern:

Be it known that I, FRANK McCARTY, of Martin's Ferry, in the county of Belmont and State of Ohio, have invented a new and Improved Heater, of which the following is a full, clear, and exact description.

The invention relates to hot-air furnaces; and its object is to provide a new and improved heater which is comparatively simple and durable in construction, very effective in operation, and designed for use in street-cars and buildings, and arranged for burning coal, gas, coke or other fuel without danger of accidentally spilling or discharging the burning fuel.

The invention consists of certain parts and details and combinations of the same, as will be fully described hereinafter and then pointed out in the claims.

Reference is to be had to the accompanying drawings, forming a part of this specification, in which similar characters of reference indicate corresponding parts in all the figures.

Figure 1 is a side elevation of the improvement as applied to the under side of a car. Fig. 2 is a sectional side elevation of the same on the line 2 2 of Fig. 3. Fig. 3 is a sectional plan view of the same on the line 3 3 of Fig. 2. Fig. 4 is a sectional plan view of an air-chamber and its inlet-ducts, the section being taken on the line 4 4 of Fig. 2; and Fig. 5 is a transverse section of the improvement on the line 5 5 of Fig. 2.

The improved heater is provided with a casing A, in which is formed a chamber B adapted to receive the fire-pot C, made in the usual conical shape, as illustrated in Fig. 2, so as to form between its walls and the walls of the chamber B a space for the circulation of air, to prevent breaking of said fire-pot. The lower end of the fire-pot C extends upon a grate D of any approved construction, below which is arranged an ash-pit E, securely attached to the lower end of the chamber B, as plainly indicated in the drawings. The ash-pit E is provided with the usual door E' in the form of a damper to admit air to the ash-pit and to the chamber B, grate-bars D and fire-pot C. In the fire-pot itself are arranged openings C' a short distance above the grate D, so that air can circulate from the chamber over the fuel

in the lower part of the fire-box to insure complete combustion. The fuel is introduced into the fire-pot at the upper end thereof through a channel F extending to the outside of the heater, with the outer end closed by a door F'.

The top flange of the fire-pot C is provided with recesses or cut-outs C², to permit the air to pass from the upper end of the chamber B into the spaces above the fire-pot, to then mingle with the heat and gases generated by the burning fuel in the said fire-pot. The smoke and gases pass from the upper end of the fire-pot over the apertured wall G through the three channels G', G² and G³, separated from each other by hot-air flues H disposed vertically, to cause a direct draft, as herein-after more fully described. In the center channel G' is arranged a valve I, secured at its lower end on a transversely-extending shaft I', extending to the outside of the furnace, to carry at its outer end a handle I² adapted to be taken hold of by the operator to open and close the said valve I, to cause the smoke and gases to pass directly from the fire-pot through the center channel G' through a smoke-pipe J when the valve I is open, or when the said valve is closed to cause the smoke and gases to pass to the side channels G² and G³ and the said smoke-pipe J. The latter connects with a second smoke-pipe J' in the outer casing K attached to the casing A, as is plainly shown in the drawings, the said casing K forming with the casing A a space for the passage of the air to be heated by the burning fuel in the fire-pot C.

The casing K is provided directly under the channels G', G² and G³ with a transversely-extending air-chamber L, into which open the air-ducts N and O, of which the air-duct N extends forwardly, as is plainly shown in Figs. 1, 2, 3 and 4, while the other air-duct O is arranged at one side of the casing K and opens rearwardly, as indicated in Fig. 4.

A valve P arranged in the chamber L serves to open or close either of the ducts N or O—that is, when the car is traveling in a forward direction, then the duct N is opened to admit air to the chamber L, while the valve P closes the other duct O. When the car is on the return trip, the valve P is changed so as

to close the duct N, as indicated in dotted lines in Fig. 4, to open the duct O to permit air to readily pass into the said duct. Thus, whether the car goes in a forward or backward direction, air will always be admitted into the chamber L to furnish a sufficient supply of air to be heated to properly heat the car.

The valve P is secured on a vertically-disposed shaft P', journaled in suitable bearings in the chamber L and extending from the bottom thereof to the outside, the lower end of the shaft P carrying an arm P², connected by a link P³ with a lever P⁴ fulcrumed on the duct N, as indicated in the drawings. The upper end of the lever P⁴ is connected by a rope P⁵ with the interior of the car, so that the conductor thereof upon pulling the said rope P⁵ can change the position of the valve P to open or close either of the ducts N or O.

The chamber L is connected at its sides and front with a top chamber L², from which leads the flue L³ into the interior of the car, building or other place to be heated.

Now it will be seen that when the heater is in use, the air passing to the chamber L from either duct N or O passes around the chamber B and channels G', G² and G³, to finally reach the chamber L² and the outer flue L³. Part of the air passes directly from the chamber L to the chamber L² by the vertical flues H, forming a division-wall for the channels G', G² and G³.

The lever P⁴ is preferably provided with a weight P⁶, so as to hold the valve P closed normally on the duct O until the operator pulls the rope P⁵.

It will further be seen that should the fire-pot C crack or burst into pieces, then the gases of the burning fuel cannot pass into the air chambers and ducts, as the fire-pot is set in the chamber B separate from the said hot-air chamber and channels.

Having thus fully described my invention, I claim as new and desire to secure by Letters Patent—

1. A heater comprising a closed inner casing having a fuel opening in the upper portion of its front end, a fire pot in the casing, an ash pit therebelow, three channels extending rearwardly and downwardly from the upper edge of the fire pot, the side channels communicating at their lower rear corners with the middle channel, vertical parallel hot air flues forming the walls of said flues next to the fire pot, a smoke outlet in the rear end of the casing in line with the middle channel, a damper hinged at its lower edge in the bottom of the middle channel to swing vertically into a perpendicular position and close direct draft through said middle channel or swing rearwardly and downwardly to open the middle channel and close the side channels, an outer casing spaced from and surrounding the inner casing, air inlets in the outer casing below the said three channels and a damper mechanism for said air inlets, substantially as described.

2. The combination with the inner casing containing the fire pot, of the outer hot air casing surrounding the said inner casing, air inlets being provided in one side wall and in the rear wall respectively of the outer casing, a horizontally swinging damper pivoted in the angle of the outer casing between said two inlets to close either one as may be desired, a crank connected with the axis of said damper, a vertically rocking counterbalanced lever pivoted between its ends and linked at its lower end to the said crank to hold the damper closed over one inlet, and an operating device for said lever, substantially as described.

FRANK McCARTY.
